METAL ROLL FORMING MACHINE

Karl Breuer, Toronto, Ontario, Canada

Application March 18, 1942, Serial No. 435,195

21 Claims. (Cl. 80—34)

This invention relates to metal roll forming machines and more particularly to a unit for use in conjunction therewith.

In metal rolling machines employing horizontally disposed rollers for shaping metal passed therebetween, it has been usual to employ side pressure rollers disposed on a vertical axis for engaging the material from the sides as it is passed or before or after it is passed through the horizontal rollers to shape the metal according to specific requirements. In the past it has been usual to mount the side pressure rolls on the laterally spaced apart vertically extending bearing supports for the horizontal rolls. This has required that these bearing supports be specially designed and constructed to receive mountings for the side pressure rolls. Moreover, these supports must then each carry side pressure rolls or such rolls would have to be demounted and transferred and remounted from one pair of bearing supports to another as the necessity arose. This, of course, is disadvantageous because it involves either a large number of parts or considerable work in transferring and demounting and remounting parts. On the other hand, such mountings have a particular disadvantage due to the fact that it is difficult to adjust the side pressure rolls vertically upwardly or downwardly in such a structure and in fact to provide for such an adjustment would require either a cumbersome structure or a cumbersome adjusting operation.

A further method of mounting the side pressure rolls has been to provide a special mounting base between adjacent pairs of roller assemblies in which the pairs of vertically extending bearing supports for such assemblies are spaced apart longitudinally of the machine to permit the mounting of such base. In this case, the rollers usually project upwardly from the base on vertical spindles and are employed for applying a limited side pressure, in which operation the side pressure rolls are not used directly in combination with the horizontal pressure roll assemblies. Such structures, therefore, are not capable of the application of a desired degree of side pressure or a heavy pressing operation and are not capable of longitudinal adjustment on the machine in relation to the horizontal roller assemblies to perform side pressure operations at various locations as required apart from the fact that they take up space in the machine which is not necessary.

These disadvantages may be avoided by providing a unit incorporating side pressure rolls

which may be employed independently of the bearing supports referred to and through which greater flexibility of operation may be attained.

It is, therefore, an object of the present invention to avoid the disadvantages of prior practice and to produce a unit embodying side pressure rolls which may be transferred to any position on the machine to operate in conjunction with any given pair or pairs of horizontally disposed pressure rolls and which will not take up any more space than is normally available throughout the length of the machine.

A further object of the invention is to produce such a unit which provides an independent mounting for the side pressure rolls and which may function independently of the bearing supports of the horizontal rolls of the machine and other parts of such assemblies.

A further object of the invention is to provide a unit of this character through which the outwardly directed strain imposed by the pressure rolls is not directed on the bearing supports.

A still further object of the invention is to provide a unit of the character referred to which may be readily adjusted both vertically upwardly and downwardly and horizontally inwardly and outwardly, in a relatively simple manner.

A still further object of the invention is to provide a unit of this character which is generally simple in construction and which may be efficiently mounted in the machine in a simple manner.

With these and other objects in view, the invention generally comprises a supporting unit carrying side pressure rolls or elements in opposed spaced apart relation from one another and designed to engage material passing through the roll forming machine, said unit being bodily removable relatively to units of the roll forming machine to cooperate with different roller assemblies thereof. Preferably the unit includes means for adjusting the rolls vertically upwardly or downwardly and horizontally towards and away from one another, and also means for adjusting said elements so that they may be disposed at an incline to their normally vertically disposed axes. The unit is preferably mounted from the bed of the machine and maintained in position by its own weight and in conjunction with simple means for preventing shifting movement of the unit where movement might take place under influence of the metal passing through the machine and acted upon by said unit.

The invention will be clearly understood by reference to the following detailed specification.

taken in conjunction with the accompanying drawings.

In the drawings:

Fig. 1 is a perspective view of the unit as a whole.

Fig. 2 is a perspective view of the unit shown in conjunction with a pair of horizontally disposed pressure rolls mounted in conventional bearing supports.

Fig. 3 is a transverse section taken through the bearing supports of a pair of horizontally disposed pressure rolls in a rolling mill illustrating the horizontally disposed pressure rolls and the mounting and disposition of the side pressure rolls according to the present invention.

Fig. 4 is a top plan view of a unit according to the present invention mounted between a pair of bearing supports for a pair of horizontally disposed pressure rolls with the upper of said horizontally disposed rolls removed for the sake of clarity.

Fig. 5 is a transverse section taken through the assembly shown in Fig. 2 in order to illustrate parts of the structure more clearly.

Fig. 6 is a perspective detail partly in section of one form of means which might be employed for retaining the unit of the present invention from movement under influence of the movement of the metal being shaped; and

Fig. 7 is a side elevation of part of the rolling mill bed showing alternative means for maintaining the unit from movement in respect to its normal position of mounting.

Referring to the drawings, A indicates the unit as a whole which in the preferred form includes a pair of side members 10 and 11 designed to support side pressure rollers B which are rotatably mounted in suitable transverse slots 12 in the side members. The side members 10 and 11 may take any desirable form and as here shown are formed with enlarged portions 13 to receive therethrough upper and lower connecting rods 14 and 15 respectively which pass through the members and are secured by means of suitable nuts or the like 16 disposed on the outside face of the members 10 and 11. This construction in general, therefore, forms supporting framework for the side pressure rolls disposing them in horizontally spaced apart opposed relation to one another. This frame is suitably supported by means of standards C which pass through the ends of the side members 10 and 11 and are secured on the upper side of these members by nuts 17 and on the lower side by nuts 18, the reduced upper end 19 of these standards being screw-threaded. Thus, by suitably manipulating nuts 17 and 18 of each standard, the side members 10 and 11 may be adjusted, upwardly or downwardly on these standards. Likewise, by adjusting the nuts 16 on the pairs of connecting rods 14 and 15, the side members 10 and 11 may be adjusted horizontally inwardly or outwardly.

I preferably provide enlarged bores 20 in the side members 10 and 11 for the passage of the connecting rods 14 and 15 so that by tightening the adjusting nuts on the rods 14 to a greater extent than those on the rods 15, the side members may be tilted so that the side pressure rollers B may incline downwardly towards each other. By reversing this adjustment and tightening the nuts on the rods 15 to a greater extent than those on the rods 14, the side pressure rollers may be caused to tilt upwardly and towards each other. In this connection it will be appreciated also that the rolls B are independently adjustable vertical-

ly upwardly or downwardly since by reason of the enlarged bores 20 the side member 10 may be disposed at a higher elevation than the side member 11 and vice versa. As a whole, therefore, the simple unit is capable of adjustment in various ways and in a simple manner.

In Figs. 2 to 5 the unit is shown disposed in position to cooperate with the horizontally disposed pressure rollers 21 and 22 carried on the horizontal shafts 23 and 24 which are journaled in the vertically extending bearing supports 25. These supports may be constructed in an extremely simple form merely including a slot 26 at their upper ends to carry the bearings 27 in vertically slideable relation controlled by suitable screws 28. Thus, to mount the unit A in association with the rollers 21 it is only necessary to remove the upper horizontal roller 21 and to cause the unit to straddle the lower roller 22 and shaft 24, the unit being supported readily by the standards C. The said pressure rollers B are then disposed on each side of the horizontal pressure rollers 21 and they may be disposed forwardly or rearwardly of the rollers 21 and 22 or directly alongside of them merely by shifting the unit on the bed plate of the mill.

The unit is, of course, held from sliding movement along the bed plate of the machine in any suitable manner. Normally the weight of the unit will tend to maintain it in the desired position, but due to the fact that the metal being shaped and passing through the mill would have a tendency to cause the unit to shift in the direction of its travel, a means of offsetting such tendency is necessary. This may be accomplished in several ways. For instance, the unit disclosed in Fig. 1 includes laterally projecting arms 29 projecting from the side members at one end thereof. These arms are designed to project beyond the sides of the vertical bearing supports 25. Thus, by mounting in these projecting arms an adjusting screw 30, the end of which is designed to abut against one side of the bearing supports, the unit A may be held from sliding movement. Moreover, it will be appreciated that the adjusting screws 30 form a means of adjusting the unit relatively to the rollers 21 and 22 so that the side pressure rollers B may be disposed in various positions as above referred to with respect to the rolls 21 and 22.

This is a very important feature as it permits very fine adjustment of the side rolls to position them accurately to a fine degree in relation to the horizontal rolls, which fine adjustment is necessary in various instances to overcome defects in the rolling operation.

Instead of employing the bearing supports 25 as a means for preventing movement of the unit A, a separate means may be provided such as in the case where the bearing supports might be widely spaced apart so as not to be available for this purpose as above described. In this instance a retaining member 31 (see Fig. 6) may be provided as shown. This includes a base plate 32 with spaced apart upwardly projecting posts 33. The plate may be bolted or otherwise secured to the bed of the mill and the upwardly projecting posts cooperate with the adjusting screws 30 of the unit A in the same manner as the bearing supports 25 as above described.

Another form of retaining means that might be employed is shown in Fig. 7 wherein a pair of arms 34 are provided, swingably mounted as at 35 on projecting bolts or the like associated with the side members 10 and 11. In this instance,

the projecting ends of bolts 14 and 15 might be employed. The arms 34 may be provided with a hook-like extremity 36 designed to enter one of the channels 37 normally provided in the rolling mill bed and to engage one edge thereof. The arm 34 may be suitably orificed as at 38 through which the arms may be adjusted relatively of the unit A thus providing for positioning of the unit at various desired points relatively to the rolls carried by the bearing supports 25. In addition, a second set of arms 39 may be provided extending generally in the opposite direction to arms 34 and entering into another channel 37 of the bed plate of the mill. These arms might be adjusted similarly to the arms 34. Alternatively either the arms 34 or the arms 39 may be employed.

The unit provided by the present invention may be used with particular facility to accomplish various operations and without the necessity of employing cumbersome adjusting structures. The side pressure rolls are employed mainly in cooperation with the horizontally disposed pressure rolls which exert a vertically directed pressure upon the material passing therebetween. It should be noted, however, that the unit does not always function with the horizontally disposed pressure rolls since in shaping metal to certain contours it may be desirable to eliminate in certain units actual use of the horizontal pressure rolls and to substitute in cooperation with the unit a mandrel or other device or devices cooperating with the side pressure rolls for producing the final desired shape.

The side pressure rolls on the whole function to effect a horizontally applied pressure or pressure directed at an angle between the horizontal and vertical, thus, cooperating in forming the material into a predetermined shape. This pressure may be exerted at a predetermined horizontal plane having regard to the fact that the side members may be adjusted vertically, upwardly or downwardly and such pressure may also be applied at predetermined similar or different points spaced apart horizontally, by reason of the adjustment of the side members towards and away from each other either independently or together. Moreover, pressure may be applied in predetermined, different, horizontal planes at the same time by reason of the fact that the side member 10 may be disposed at a different level to the side member 11 or vice versa, since each side member is independently adjustable vertically. Finally, adjustment may be effected by way of the connecting rods 14 and 15 in such a way that the tightening nuts 16 on the rods 14 may be tightened to a degree greater than that on the rods 15 or vice versa, to cause the side members to incline downwardly towards each other or upwardly towards each other so as to cause the side pressure rollers B to exert a pressure at an angle between the horizontal and vertical.

From the point of view of adjustment it will be seen that the unit provides for diversified use in a simple way but apart from this it simplifies a number of problems in respect to the mounting of the side pressure rolls as will readily be appreciated. So far as the bearing supports 25 are concerned it is apparent that the unit relieves any abnormal outward or laterally applied strain imposed thereon as in the case where the side pressure rolls were mounted from these bearing supports. Instead any strain set up by the pressure of these rolls in performing their work is

taken by the side members 10 and 11 and the simple connecting rods 14 and 15 which may be made of drill rod steel. In other words, the unit may be constructed economically to withstand any appreciable strain. Furthermore, it will be appreciated that the unit of the present invention provides for a wide degree of adjustment which, is not possible in the case where the rolls are mounted as was the practice in the prior art.

10 It is also apparent that the unit may be shifted from one position to another on the machine in a very simple manner so that it may be operated at that point on the machine where it is desired, without it being necessary to provide special fittings on the bearing supports.

While the side pressure rolls B are normally employed for side pressure operations it will be appreciated that instead of these rolls pressure shoes or guide members might be employed. In 20 the following claims, therefore, the term "side pressure elements" is employed which is designed to define rolls or other pressure members that might be employed.

What I claim as my invention is:

1. The combination with a roll forming machine having horizontal pressure rolls and supports for mounting said rolls, of a unit including vertically disposed side pressure elements, designed to engage metal passing through said horizontal rolls, including means for positioning said side pressure elements directly adjacent to the nip of said horizontal rolls and flanking the latter in cooperative relation therewith, and independently of the supporting means for said horizontal rolls, said vertical elements being positioned in horizontally spaced relation to one another and in spaced apart relation to the bed of the machine, said unit being bodily removable relatively to the machine whereby said unit may be disposed to cooperate with any selected roller assemblies thereof.
2. A unit as claimed in claim 1 in which means is provided for adjusting said side pressure elements towards and away from each other.
3. A unit as claimed in claim 1 in which the side pressure elements are adjustable horizontally, vertically and at an angle to the horizontal and vertical.
4. A unit as claimed in claim 1 in which means is provided in connection with said unit for anchoring said unit against shifting movement on the machine, said means including adjusting means whereby said unit may be adjusted to position the side pressure elements in spaced relation to the roller assemblies in a direction at right angles to their normal axes.
5. A unit for use in roll forming machines and like for supporting and positioning side pressure elements in relation to horizontal roller assemblies of the machine and designed to engage metal passing through the horizontal rollers, comprising supporting means for the side pressure elements for disposing said elements in opposed horizontally spaced apart relation to one another directly adjacent to the nip of said horizontal rolls and independently of the mounting for said horizontal rolls, means for adjusting said supports horizontally towards and away from one another, means for adjusting said supports vertically upwardly and downwardly, and means for mounting said supports in vertically spaced relation to the bed of the mill, said unit being bodily removable relatively to the machine whereby said unit may be disposed to cooperate with any selected roller assemblies thereof.

6. A unit as claimed in claim 5 in which a means for adjusting the supports horizontally includes means for adjusting each support independently of the other and in which means for adjusting said supports vertically upwardly and downwardly includes means for adjusting each support independently of the other.

7. A unit as claimed in claim 5 in which means is provided for adjusting said supports at an angle to the vertical and horizontal to dispose said side pressure members at an incline.

8. A unit as claimed in claim 5 in which means is provided for securing the unit against shifting movement in the direction of movement of the metal engaged by said elements.

9. A unit for use in roll forming machines and the like for supporting and positioning side pressure elements in relation to horizontal roller assemblies of the machine and designed to engage metal passing through the mill, comprising supporting means for the side pressure elements for disposing said elements in opposed horizontally spaced apart relation to one another directly adjacent to the nip of said horizontal rolls and independently of the mounting of the latter, pairs of upper and lower rods connecting said supports to form a framework, means in connection with said rods for adjusting said supports towards and away from each other, means for mounting said framework in spaced apart relation to the bed of the mill, and means in connection with said mounting means for adjusting said supports in vertically spaced relation to the bed of the mill.

10. A unit as claimed in claim 9 in which the supports are independently adjustable both in the horizontal and vertical direction.

11. A unit as claimed in claim 9 in which the supports are formed with bores through which said rods are designed to pass, the bores being of a diameter larger than the diameter of the rods whereby upon adjustment of the adjusting means of one pair of rods to a greater extent than the other pair of rods will cause said supports to tilt at an angle.

12. A unit for use in roll forming machines and the like for supporting and positioning side pressure elements designed to engage metal passing through the machine comprising supporting means for the side pressure elements for disposing said elements in opposed horizontally spaced apart relation to one another, pairs of upper and lower rods connecting said supports to form a framework, means in connection with said rods for adjusting said supports towards and away from each other, means for mounting said framework in slidable bearing engagement with the bed of the machine and in spaced apart relation thereto, means in connection with said mounting means for adjusting said supports in vertically spaced relation to the bed of the machine, and means connected with said framework for engaging parts of the machine for retaining said unit against shifting movement.

13. A unit as claimed in claim 12 in which the means for preventing shifting movement of the unit includes adjusting means to position said unit in a selected relation to other parts of the machine.

14. A unit for use in roll forming machines and the like for supporting and positioning side pressure elements designed to engage material passing through the machine and to cooperate with roller assemblies thereof, comprising supporting means for the side pressure elements, means for

mounting said supporting means from the bed of the machine in slidable bearing engagement therewith and independently of other parts of the machine, said supporting means positioning the side pressure elements in horizontally spaced apart relation to one another, means for adjusting said side pressure elements towards and away from each other, and means in connection with said unit for engaging other parts of the machine 10 for retaining said unit against shifting movement, said unit being bodily removable relatively to the machine whereby said unit may be disposed to cooperate with selected roller assemblies thereof.

15. A unit for use in roll forming machines and the like for supporting and positioning side pressure elements designed to engage metal passing through the machine and to cooperate with roller assemblies thereof, comprising supporting means for the side pressure elements, adjustable means for mounting said supporting means from the bed of the machine, said unit being mountable between supports for said roller assemblies and independently thereof to dispose said pressure elements directly adjacent to the nip of the roller assemblies, said supporting means positioning the side pressure elements in horizontally spaced apart relation to one another, said unit being bodily removable relatively to the machine whereby said unit may be disposed to cooperate with selected roller assemblies thereof.

16. A unit for use in roll forming machines and the like for supporting and positioning side pressure elements designed to engage metal passing through the machine and to cooperate with roller assemblies thereof, comprising supporting means for the side pressure elements, means for mounting the supporting means in spaced relation to the bed of the machine in slidable bearing engagement therewith, said supporting means positioning the side pressure elements in horizontally spaced apart relation to one another, said unit being bodily removable relatively to the machine whereby said unit may be disposed to cooperate with selected roller assemblies thereof, and means in connection with said unit extending between the latter and the machine for anchoring the unit against shifting movement on the machine.

17. A unit as claimed in claim 16 in which the supporting means is provided with laterally projecting members engageable with upwardly projecting parts of the machine to anchor said unit against shifting movement.

18. A unit as claimed in claim 16 in which an anchoring member is provided connected with the bed of said machine and having an upwardly extending structure to engage said unit to prevent shifting movement of the latter on the machine.

19. A unit as claimed in claim 16 in which connecting means is fastened to the unit and designed to connect with a portion of the machine to prevent shifting movement of said unit on said machine.

20. A unit as claimed in claim 16 in which the means for anchoring the unit against movement is adjustable to adjust the position of the side pressure elements relative to the roller assemblies of the machine in a direction at right angles to the axes of said roller assemblies.

21. A unit for use in a roll forming machine and the like for supporting and positioning side pressure elements designed to engage metal passing through the machine including an assembly 75 for deforming the metal in predetermined man-

ner comprising supporting means for side pressure elements, means for mounting said supporting means from the bed of the machine, said supporting means positioning the side pressure elements in horizontally spaced apart relation to one another and directly adjacent and cooperatively related to said deforming assembly, said

unit being bodily removable relatively to the machine whereby said unit may be disposed to co-operate with selected deforming assemblies thereof and means for anchoring the unit against shifting movement relatively to the bed of the machine.

KARL BREUER.
